[57] CLAIM

The ornamental design for a pistol magazine, as shown and described.

DESCRIPTION

FIG. 1 is a perspective view showing the top, the left side and the rear of the pistol magazine which forms our invention;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a left side elevational view showing our pistol magazine moving into receipt by a pistol, the phantom lines representing the pistol being shown for illustrative purposes only and forming no part of our new design.
